TIRE

Marco Maxemovich, Warren, Mich., assignor to Uniroyal,
Inc., a corporation of New Jersey

Filed Apr. 29, 1966, Ser. No. 2,074

Term of patent 14 years

(Cl. D90—20)

Fig. 1.

FIG. 1 is a perspective view of a tire embodying my new design, it being understood that the full line portion is repeated throughout the circumference of the tire, shown by means of broken lines;

FIG. 2 is a sectional view taken on a plane including the rolling axis of the tire of FIG. 1 but on the same scale as FIGS. 3 and 4;

FIG. 3 is a fragmentary elevation of the full line portion shown in FIG. 1;

FIG. 4 is a fragmentary plan of the full line portion shown in FIG. 1; and

FIG. 5 is a fragmentary sectional view taken on line 5-5 of FIG. 3.

The dominant features of my design reside in those portions shown in full lines in the drawings.

I claim:

The ornamental design for a tire, substantially as shown and described.
